FINGER RING OR SIMILAR ARTICLE

David R. Cohen, Los Angeles, Calif.

Application January 13, 1950, Serial No. 7,226

Term of patent 14 years

(CL. D45—10)

To all whom it may concern:

Be it known that I, David R. Cohen, a citizen of the United States, residing at Los Angeles, in the county of Los Angeles, State of California, have invented a new, original, and ornamental Design for a Finger Ring or Similar Article, of which the following is a specification, reference being had to the accompanying drawing, forming part thereof, in which:

Fig. 1 is a perspective view of a finger ring, embodying my new design;

Fig. 2 is a side elevational view thereof; and

Fig. 3 is a top plan view of the finger ring.

I claim:

The ornamental design for a finger ring or similar article, substantially as shown.

DAVID R. COHEN.
